WIRE TYING MACHINE

Charles E. Evans, Seattle, Wash.

Application December 3, 1932, Serial No. 645,549

26 Claims. (Cl. 100—31)

This invention relates to bundle binding machines, and more particularly to machines of that class by which a required length of a metal band, strip or wire may be drawn from a spool, or supply roll, wrapped tightly and secured about a package, box or bundle of limited dimensions, then severed to release the wrapped bundle from the supply, while that end of the severed band leading from the supply remains gripped in the machine and properly threaded ready for another wrapping operation.

It is the principal object of the present invention to provide certain improvements in machines of the type disclosed in United States Patent No. 1,875,260 to Parker whereby they are adapted to the welding together of overlapped ends of a band, strip or wire drawn about a bundle instead of joining them by the twisting or tying operation as is the method employed in the Parker machine.

It is also an object of this invention to provide a joint or weld that will lie flatly against the face of the bundle regardless of whether it is a flat strip, or wire.

More specifically stated, it is the object of the present invention to provide a bundle wrapping or binding machine comprising mechanism that is automatically operable to wrap a strip, band or wire, once about a package or bundle, to draw it taut with its ends in overlapped relation across a platen which is one terminal of an electric welding circuit; also comprising movable contacts connected to the other side of the welding circuit and automatically operable against the said overlapped parts of the band to close a welding circuit therethrough and thus join these parts permanently together.

It is also an object of this invention to provide band grippers of novel form; one of which is arranged to hold the end of the band during the wrapping operation and the other is arranged to be actuated to grip and hold the overlapping part of the band, at the end of a wrapping operation prior to the welding and band severing operation.

Another object of this invention resides in the provision of novel means for lifting the bundle encircling portion of the band clear of the path of the second gripper as it is functionally actuated to secure a hold on that part of the band leading directly to the supply.

Still another object of the invention resides in the provision of novel means for severing the ends of the band at opposite sides of the weld to release the bundle from the supply of bind-

ing material and ready for removal from the machine.

Another object resides in the provision of means operable with the band cutters for stripping the bundle securing band from the platen after welding.

Other objects reside in the details of construction of the various parts; in the means for actuating them in proper sequence and in their relationship and mode of operation.

In accomplishing these objects, I have provided the improved details of construction, the preferred forms of which are illustrated in the accompanying drawings, wherein—

Fig. 1 is a front elevation of a bundle wrapping machine embodying the present invention, a part of the main frame and housing being broken away and shown in section for better illustration.

Fig. 2 is a top view of the band welding, gripping and cutting mechanism, with the cover plate removed from the housing of the latter for better disclosure of the contained mechanism.

Fig. 3 is a vertical section of the same, taken substantially on the line 3—3 in Fig. 2.

Fig. 3a is a cross sectional detail diagrammatically illustrating the open space between sections of the table top for passage of the binding band about a bundle for a wrapping operation.

Fig. 4 is a view, showing in longitudinal, vertical section, one of the band gripping, cutting and welding units.

Fig. 5 is a side view of one of the band separating pilots.

Fig. 6 is an inside elevation of the band welding contacts and mechanism directly associated therewith.

Fig. 7 is a sectional detail of one of the welding contacts.

Fig. 8 is a perspective view of the complementary parts of one of the band grippers.

Fig. 8a is a view illustrating an alternative form of gripper jaw.

Fig. 9 is a cross sectional view on the line 9—9 in Fig. 3.

Fig. 10 is a cross section on the line 10—10 in Fig. 3.

Fig. 11 is a view illustrating the relationship in the setting on their actuating shaft of the actuating cams for the two welding contacts.

Fig. 12 is a detail showing the relationship in the setting on their actuating shafts of cams for actuating the grippers, band separating pilots and carriage which mounts the band cutters and stripper hook.

Fig. 13 is a detail, illustrating the wrapping of a

band about a bundle and the overlapping of its ends beneath the platen for the welding operation.

Fig. 14 is a detail, illustrating the pivoting 5 action of the gripper which holds the band end at the start of a wrapping operation.

Fig. 15 is a plan view of the main driving mechanism of the machine.

Fig. 16 is a perspective view of the starting and 10 stopping mechanism.

Fig. 17 is a section taken on line 17-17 in Fig. 15.

Fig. 18 is a view diagrammatically showing in 15 elevation the position of the band and wrapping wheel at the start of an operation, and adjacent thereto, in plan view, the relative positions of the band grippers, cutters and band separating pilots at the start of the same wrapping operation.

20 Figs. 19, 20, 21 and 22 are similar illustrations of the same parts, in their relative positions during a bundle wrapping operation.

Fig. 23 is a view of the parts in the position 25 following the welding operation and during the band cutting operation.

Fig. 24 illustrates the disposition of overlapped portions of a wire band used for wrapping a bundle.

Fig. 25 illustrates how the band of Fig. 24 30 flattens itself against the bundle when released.

Briefly described, the present machine embodies mechanism operable to draw off a required length of metallic band, wire or strip from a source of supply, wrap it tightly about a 35 bundle, box, package, or the like, of limited size, then join overlapped portions of the band in a welded joint and finally sever the band to release the wrapped bundle. Preparatory to a bundle wrapping operation, the band, wire or 40 strip is extended from a source of supply, through suitable tension producing means, over slack take up sheaves, then about guide rolls on a wrapping element in the form of a rotatably movable ring gear encircling the bundle to be 45 wrapped, and thence to a gripper at one side of a welding platen. The ring, incident to its rotation, pays out the band therefrom, as drawn from the supply, and wraps it tightly about the bundle. The extent of travel of the ring is such 50 as to carry the band to a position at which portions thereof will be overlapped across the welding platen, then a second gripper, at the other side of the platen grips and holds the overlapping portion of the band while welding contacts are 55 actuated thereagainst to spot weld the overlapped parts together. Following this welding operation, the band is cut off closely at opposite sides of the weld but within the grippers, thereby freeing the band for stripping from the welding 60 platen and releasing the bundle for removal from the machine, but the end of the band from the source of supply is retained by the second gripper preparatory to the next bundle wrapping operation, for which the ring is then reversed in its 65 direction of rotation.

The machine is set in motion for a wrapping operation by manual actuation of a starting pedal, but it is automatically stopped at the end of each wrapping operation.

70 Referring more in detail to the drawings—

The present machine, in a preferred form of construction, comprises a main frame structure 1 which mounts and houses the principal operating parts. This frame is provided with a horizontal top, or table 2, on which the bundle or

package B is placed for wrapping. An upper frame structure 3, rigid relative to the base structure, extends above the table 2 and is provided with an opening 3a within which the bundle is located for wrapping and, if such is desired, an adjustable abutment 4 may be employed, as seen in Fig. 1, as a means for locating the bundle centrally over the welding apparatus.

Rotatably supported by the frame structure of the machine to encircle the opening 3a and 10 bundle B is the ring gear R supported by a plurality of spaced guide rollers 6 journaled, as seen in Fig. 1, on studs 6' fixed on the frame structure both above and below the table 2.

In accordance with the operation of this machine, a metallic band, strip or wire S is drawn from a supply spool, not shown, threaded through tension producing means 7, then is wrapped several times about slack take up sheaves 8 and 9, then extended across a guide sheave 10 and from the latter is passed first over a guide sheave 12 mounted by a stud 12' fixed in the frame 3 centrally over the ring gear R, then onto the ring gear about grooved guide rollers 13 that are mounted thereon at regularly spaced intervals by studs 13'. At one side, the ring gear has two grooved guide rollers 14-14' mounted thereon in close relation by studs 14a and the band S passes from the ring gear between these rollers to the gripper G or G²; the operating arrangement being such that upon rotation of the ring, the band S will be drawn from the supply and will feed from between the rollers 14-14' as it is thereby wrapped about the bundle.

The table top comprises two spaced sections 2a and 2b as seen in Fig. 3a, providing an open space s between them substantially in the plane of the binding band as carried on the ring gear so as to permit passage of the band about the bundle which, for wrapping, is placed across this open space.

The grippers G and G² are located beneath the table 2 at opposite sides of a platen P which is centrally disposed relative to the ring and flush with the table top. Since the ring gear R, in each cycle of operation, is caused to rotate approximately ninety degrees more than one complete circle, it is apparent that, starting with one end of the band held in gripper G, at one side of the platen, and the ring rotating clockwise, the band will be wrapped once about the bundle and then drawn taut with parts in overlapped relation beneath the platen. The mode of operation of this machine, as will presently be understood, provides that for one complete cycle of operation, the ring R will be rotated in one direction, then for the next cycle of operation, it will be rotated in the opposite direction. In either instance, opposite ends of the bundle binding length will be overlapped beneath the welding platen.

The tensioning means 7 may be of any suitable character whereby a desired tension may be maintained on that length of the band extending about the ring to the gripped end, and the slack take up means is such as to keep the band taut about the ring gear, especially at the time of reversal in direction of rotation of the ring. As here shown, the grooved sheave 8 is revoluble on a fixed stud 8' while the sheave 9 is mounted on a stud 9' carried by a slide 15 movable from and toward sheave 10 on a guide rod 16 supported by the main frame 1. A coiled spring 17 is attached to the frame and to the slide to pull the 75

sheave 9 away from sheave 8 thus to maintain the band, which is wrapped about the sheaves 8 and 9, under tension. When slack occurs in the band S at the start of each wrapping operation, as presently understood, it is taken up by the downward travel of the sheave 9 under pull of spring 17.

The means provided for driving the ring gear and whereby its direction of rotation will be reversed for successive wrapping operations, is illustrated in Figs. 1, 15 and 16, wherein 20 designates an electric driving motor operatively connected by means of a sprocket chain belt 21 with a clutch driving shaft 22; the belt passing about 15 sprocket wheels 23 and 24 fixed on the motor shaft 25 and shaft 22, respectively. Shaft 22, through the mediacy of a suitable clutch mechanism 26 drives a shaft 27 equipped with a gear 28 in driving mesh with a larger gear wheel 29 on a 20 cross shaft 30. Shaft 30 in turn has a small gear 31 keyed thereon in driving mesh with a large gear wheel 32 on a cross shaft 33. Thus, through this gear connection, the wheel 32 will be rotated by the motor at a reduced speed.

Operating in driving mesh with the ring gear R is its driving gear wheel 34 that is fixed on a cross shaft 35 driven by a gear wheel 36 keyed thereto. Gear 36 in turn is driven by a gear 37 fixed on a supporting shaft 38, and this is 30 driven by a gear 39 fixed thereto. A gear toothed segment, 40, supported by a pivot 41, meshes with gear 39 and a link 42 is pivotally connected at one end to the segment as at 43 and pivotally connected eccentrically to gear 32, as at 44, so 35 that rotation of gear 32 will cause an oscillatory movement of the segment and this, through the gearing provided will cause rotary movements of the ring gear. It is apparent that for one direction of oscillation of the segment 40, the ring 40 R will be rotated in one direction, and that for its travel in the opposite direction, the ring will be rotated in a reverse direction; the ratio of the various gears in this instance being such that the travel of the ring gear in each direction will be approximately one and one-fourth 45 turns, and at each limit of its travel, the guide rollers 14—14' will be substantially in alignment horizontally with the grippers G or G², as will be observed by reference to Figs. 18 and 21 which 50 respectively, show the position of the ring R at the start and finish of a wrapping operation.

To control the starting of the machine, I provide a shifting yoke 45 for the movable element 26' of clutch 26. This yoke is fixed on a rocker shaft 46 rotatably supported in the machine frame transversely below the shafts 27 and 30. Fastened rigidly to the shaft 46 is an upwardly directed arm 47 and this is connected at its end by a link 48 with a rocker arm 49 fixed on a 60 cross shaft 50 rotatably mounted in the main frame. A foot pedal 51 is fastened to shaft 50 and this extends to the back of the machine. Also there is a foot pedal 52 at the front of the machine extending from a supporting pivot shaft 65 53. This latter pedal has a crank arm 54 extended downwardly therefrom connected by a link 55 with a lever arm 56 fixed to and extending upwardly from cross shaft 50. Thus, the arrangement provides that by downward pressure 70 of either foot pedal 51 or 52 the rock shaft 50 will be actuated to shift the clutch element 26' for starting the machine by reason of its thus effecting a driving connection between the shafts 22 and 27.

75 For automatically stopping the machine at the

end of each cycle of operation, a trip dog 58 is mounted on the end of the rocker shaft 46 as seen in Fig. 16, and this dog has an inclined cam surface 59 arranged to be engaged by an oppositely inclined surface of one of two cams 60 fastened 5 at diametrically opposite points of a wheel 61 fixed on the shaft 33. The wheel 61, as presently understood, rotates one-half turn for each cycle of operation and the cams 60 are so located that one of them engages the dog 58 at the end of 10 each cycle, thereby to rock the dog outwardly and thus, through the mediacy of the rocker shaft 46, throw the yoke 45 forwardly to disengage the driving clutch.

It will be mentioned here that the travel of 15 the machine, after engagement of a cam 60 with the dog 58 is just enough to carry the cam past the dog, thereby removing the possibility of its interfering with the manual setting of the clutch in starting the next wrapping operation. 20

Coincident with release of the clutch mechanism, a brake is applied to stop the machine. The brake mechanism consists of a brake drum 63 fixed on shaft 27 and a brake band 64 applied thereto, and supported from the machine frame. 25 The brake band is tightened to apply the brake by the shifting of a lever 65 which is pivotally connected to the yoke 45, as at 66 in Fig. 16, so that incident to these forward and reverse swinging movements of the yoke, which, respectively, set and release the clutch, the brake will be released, 30 or will be set simultaneously therewith.

The band grippers G and G², the band cutters, release devices and their actuating mechanisms, presently described in detail, are contained within 35 in a housing 70 located beneath the table 2 and in central alignment with the axial line of the ring R as shown in Fig. 1. Spaced slightly from this housing, as seen in Figs. 2 and 3, is a housing 71 which mounts the welding platen P, the movable 40 welding contacts, and their actuating devices presently described. The two housings 70—71 are spaced, as are the two sections of the table top, to provide an open passage between them for the passage of the band S in wrapping it about a 45 bundle and for the release of the band for removal of the wrapped bundle from the machine.

The platen P is a suitable metallic plate securely fastened across the top of housing 71 in the central longitudinal line of the machine, and with 50 its top surface flush with the table top. This platen, preferably of copper, is insulated from the housing which mounts it and also from the machine and is connected with one side of an electric circuit of a character suitable for welding. As seen in plan view in Fig. 2, a wire 72 from one side of the circuit is connected by a binding screw 73 to the platen. Also, it will be observed that the end of the platen extends beyond the inner face of the housing 71 and across 60 the open space between the two housings 70 and 71.

The operative movements of the band grippers G and G² and the various mechanisms associated therewith, as well as the operation of the movable welding contacts, is directly under control of the machine driving mechanism, and the functional operations of these parts take place after the ring gear R has completed the wrapping operation and practically has come to rest following 70 this operation.

A shaft 75 operatively connects the mechanism contained in housing 70 with the main driving mechanism as seen in Figs. 1 and 15. This shaft is supported in bearings 76 provided therefor in 75

the opposite side walls of the housing 70, and its opposite ends extend from the housing; one end being equipped with a squared head 75' for reception of a wrench for manual operation of the 5 mechanism and the other end is supported in a bearing 71 in the main frame, as seen in Fig. 1.

A shaft 78 likewise is provided for actuation of the mechanism contained in housing 71 and this is disposed parallel with shaft 75 and is rotatably supported in bearings in the wall of housing 71 with its ends extended from the housing as in Fig. 2; one end having a squared head 78' for reception of a wrench or crank for manual operation or adjustment. These two driving shafts 15 75 and 78 are located above and at right angles to the direction of driven shaft 33, and at their ends are equipped with bevel driving gears 79 and 80 meshing respectively with driven gears 81 and 82 keyed on a supporting shaft 83 that is rotatably mounted in the main frame structure, parallel with and above shaft 33 as will be observed by reference to Figs. 1 and 15. The gear wheels 79 and 81 are of the same size and also gears 80 and 82 are of the same size, therefore, the shafts 20 75 and 78 will rotate in unison and the particular arrangement of gears provides that they will rotate in the same direction.

By reason of the fact that the ring gear R carries the band S about the bundle, and that the 30 welding and cutting operations must not take place until the band has been overlapped beneath the platen, the gear wheels 81 and 82 which control these latter operations are rotated only during the final travel of the ring gear 32 in each cycle of operation. It is understood that the ring gear R is caused to rotate in opposite directions for successive operations by the oscillating action of geared segment 40 which, in turn is actuated by the connecting rod 42 attached eccentrically 40 to wheel 32. Gear wheel 32 is stopped at the end of each cycle in a position at which the point of connection 44, of link 42 will be just slightly beyond dead center line drawn through centers of shafts 33 and pivot 43. Thus, for each operation 45, the segment 40 will be swung from one extreme to the other and although the welding operation takes place during final travel of the driving gear 32, there is at this time practically no movement of the segment 40 or the ring gear R 50 on the band S by reason of the fact that the point of connection of link 42 with wheel 32 is then nearing and passing across dead center line at substantially a right angle thereto, as will be understood by reference to Fig. 1.

The means for rotating the gear wheels 81 and 82 comprises a pair of toothed cam wheels 85 and 86 fixed in close relation on the shaft 33, as seen in Figs. 1 and 15. Each wheel is provided, at diametrically opposite points, with extending teeth 85'-85' and 86'-86' and one wheel is slightly advanced relative to the other so that, in accordance with the direction of rotation, the teeth 85' and 85' of wheel 85 will be slightly ahead of those 86' and 86' of wheel 86. Fixed on the inner face 65 of gear wheel 81 at diametrically opposite points, are rollers 88'-88'. Likewise mounted on the inner face of gear wheel 82 are rollers 89'-89'; the rollers of one wheel being aligned at right angles to those of the other as observed by reference to Fig. 17.

At the start of a wrapping operation, the relationship of the teeth 85'-86' of wheels 85-86 is that shown in Fig. 1 and the direction of rotation of the wheels is designated by the 75 arrow placed thereon. Therefore, since the

wheels rotate but one-half turn for an operation, the action of gears 81 and 82 under influence of the teeth 85' and 86' will take place during the final movement of the wheels, and the design of the teeth 85'-86' is such and location 5 of rollers so determined that the gear wheels will be turned exactly one-half revolution to actuate their shafts 75 and 78 accordingly and this causes the operative movements of the grippers, slides, welding contacts, cutters and strip- 10 per to occur in proper sequence.

Each gripper, G and G², comprises two complementary portions 90 and 91; the part 90 consists of an anvil that is axially rotatably supported by a mounting shank 90' in the inner 15 vertical face of the housing 71 to extend therefrom at one side of the welding platen P, and the part 91 is a tubular jaw slidably mounted in a carriage 93 in axial alignment with part 90 and reciprocally movable lengthwise in its mounting 20 from and toward the latter. At its end the anvil 90 has a V-shaped notch 92 cut therein, as seen in Fig. 8, with the side walls of the notch in vertical planes and those portions at opposite 25 sides of the notch terminating in sharpened edges 92'' serving as gripper teeth. The outer end of the sliding gripper jaw 91 is beveled off at opposite sides, as at 95, to fit within the notch 92 of part 90 and this end has a V-shaped notch 96, terminating at its base in a horizontal slit 30 97 of such depth and width as to snugly seat the band S therein, when the jaw is applied against the band.

The gripper jaws 91-91 are disposed parallel to each other and are symmetrically disposed at 35 opposite sides of the central, longitudinal line of the platen P, and are slidably fitted in substantial bearing portions 93' provided at opposite side edges of the carriage 93.

In an alternative construction, shown in Fig. 40 8a, opposite faces of the gripper jaw 91 are cut away as at 91x to permit of a closer lying together of the overlapped portions of the band and permit of easier clamping of these parts together for the welding operation. This will 45 be understood by reference to Fig. 13.

The carriage 93 in which the gripper slides 91-91 are mounted, is reciprocally movable in the frame 70 in parallel guideways 98, as seen in Fig. 10, from and toward the housing 71; 50 however, the parts 91-91 are movable lengthwise independently of the carriage and also are movable independently of each other. The actuating means for the gripper slides or jaws 91-91 comprises cam levers 99-99' pivotally 55 supported at their lower ends on a cross shaft 100 mounted in housing 70, and pivotally connected at their upper ends, respectively, as presently described to the outer ends of the slides in a type of connection whereby forward 60 or rearward swinging of the levers will effect a corresponding shifting movement of the slides. The slides 91-91 also are axially revolvable in the carriage as are also the parts 90-90 to permit rotation of each gripper about its axis while gripping the end of band S. As seen best in Figs. 3, 4 and 5, the levers 99-99' have yokes 99a at their upper ends embracing blocks 101 mounted freely on the slides between thrust 65 bearings 102 and securing nuts 103 threaded onto the ends of the slides. Pin and slot connections, as at 104, join the yoke ends of the levers with the blocks 101 of their respective gripper jaws to provide operative connections for 70 75 75

shifting the jaws toward and from their corresponding anvils 90.

The operating movements of the levers 99-99' are under control of coiled springs 108-108' attached to the levers, respectively, and to the housing, as seen in Fig. 2 to pull the levers forwardly against the action of cams 109-109' fixed on shaft 75. These cams engage cam rollers 110-110' on the levers to actuate the latter outwardly against the pull of the springs. The cams 109-109' are alike in form but are oppositely arranged on the shaft so that when one lever is retained in its outer position at which its gripper slide is retracted to open the gripper, the other is actuated inwardly, and vice versa. Each cam, as seen in Figs. 4 and 12, has a surface 109a of uniform radius extending through an arc of one hundred eighty degrees, then rounding at its ends into a surface 109b of a greater radius and extending through an arc of approximately one hundred forty degrees. When the surface of greater radius of either cam engages its respective cam roller, the lever mounting the roller will be actuated outwardly to move the gripper slide accordingly and thereby open the gripper. Likewise, when the roller passes onto the surface of lesser radius, the lever swings inwardly, thereby moving the gripper slides inwardly to gripping position. The setting of the cams as seen in Fig. 12, provides a very short interval of time during the cycle of operation that both cam rollers will be on the cam surfaces of lesser radius, and therefore both grippers will be closed; this being the period during which the overlapped sections of the band S will be gripped and held during the welding operation.

To better explain the operation, it will be assumed that the end of band S has been threaded through the tension means 7, then wound about the various slack take up and guide rollers, then onto the guide rollers 13 on the ring R as shown in Figs. 1 and 18, then passed about roller 14' and secured in gripper G by applying the end of the band to the slot 97 at the base of the V-shaped notch in slide 91 and by then rotating the cam shaft 75 to a position at which cam 109' will actuate the jaw 91 inwardly to cause the band edges to be gripped and held by the sharp edges 92'' of the parts at opposite sides of notch 92 in anvil 90; the relationship of these grippers for this position of the ring R being illustrated at the right in Fig. 18. Then, in starting the cycle of operation the ring R rotates clockwise and the attached end of the band swings radially about gripper G through the position seen in Fig. 19, then on about the bundle B through position of Fig. 20, to position of Fig. 21 at which position the band has been overlapped below gripper G and platen P and is drawn directly between the complementary parts 90-91 of the gripper G² which at this time are, by reason of the setting of cam 109, disengaged. When the band S is in this latter position, the jaw 91 of gripper G² is actuated inwardly by cam 109 to grip that run of the band S between the platen and ring gear so that both end portions of the band overlapped beneath the platen will be firmly gripped and held for the welding operation, as observed in the right hand view of Fig. 21.

It is required however, that prior to the inward action of the jaw 91 of gripper G², that the upper portion of the overlapped sections of the band, being that designated at b in Fig. 13, be

lifted out of the way of the gripper, otherwise it also would be directly in line with the gripper jaw as shown in dotted lines in Fig. 13, and would be gripped along with the lower section. For this band lifting operation I have provided a separator slide, or pilot 120 slidably mounted in the frame 70, in the guideway 98, along side of the carriage 93 as seen in cross section in Figs. 9 and 10. This pilot has a tapered forward end that is adapted, incident to forward projection 10 of the pilot, to enter between the overlapped sections of the band just at the outside of the gripper G² to lift the upper section b clear of the path of travel of the movable gripper jaw 91. This pilot 120 or separator is shown in functional position in Fig. 13.

It will here be explained that there is a similar separator, or pilot, 120' associated in a like manner with the gripper G and functionally operable when the wrapping operation is by a counterclockwise operation of the ring R; that is, when the end of the band is held by gripper G². This latter pilot 120' is shown in Fig. 13, but functions only when the wrapping operation starts with the end of the band S held in gripper G².

The separator slides 120 and 120' are of the type best shown in Figs. 1 and 5. Each is a straight bar of square cross section, slidably contained in the guideways 98 provided therefor in the carriage 93. The forward ends of these slides are beveled downwardly as at 121 to a point for easy entrance between the overlapped sections of the band. The beveled surface is such that the upper section of the band will be lifted as the slide is projected thereagainst. Each separator slide is functionally actuated incident to the functional actuation of its corresponding gripper jaw 91, but with a faster and farther movement. Normally, or when a gripper jaw 91 is retracted to a position clear of the path of the band S in the wrapping operation, the pilot also will be retracted to a corresponding extent.

As best shown in Fig. 3, each separator or pilot has an actuating bell crank lever 122 pivotally mounted on a supporting stud 124 mounted on the side walls of housing 70 rearwardly of the cross shaft 75. At their upper ends these levers 122 have pin and slot connections, as at 125, with their respective pilots or slides 120-120' so that forward or rearward action of the levers will cause a like action of the pilots. At their lower ends each bell crank lever has a short rearwardly extending lever arm 126 connected by a link 127 with an arm 128 of its corresponding clutch slide actuating lever 99. Therefore when either lever 99 is actuated forwardly to extend its gripper jaw 91 it will, as noted by reference to Fig. 3, at the same time actuate the corresponding pilot 120 forwardly, but by reason of the shorter length of lever arm 126, the pilot 120 will be caused to move faster and in advance of the gripper slide to lift the binding strip b out of the path of the gripper slide so that only that portion extended to the ring gear will be gripped by the closing of the gripper members 90-91 together.

It will be explained here that, when a jaw 91 is extended, it receives the band S in the V-shaped end notch 96 and this guides it edgewise into slot 97, then as the slide 91 enters the V-shaped notch of part 90 the sharp edges 92'' bite into the edges of the band to hold it securely against slippage in the gripper.

During the interval of time that both ends of the band are gripped and held overlapping across 75

the platen, they are pressed firmly together and welded. The welding operation is effected by the mechanism contained in housing 71 and is actuated in synchronism with the operations of the grippers by the rotation of shaft 78 as will be understood by reference to Figs. 3 and 4.

For the welding operation, I employ two contacts arranged to be successively brought up against the band to make welds that are spaced lengthwise of the band. The welding elements consist of levers or brackets 130—130' pivotally supported by pins 131 mounted in housing 71 at opposite sides of the platen. At the swinging end of each lever is a welding point or contact 132 mounted in a lug 133 on the lever. Each contact, as seen in Fig. 7, has a threaded mounting shank 132a extended through the lug and held by a nut 134. The upper ends of the contacts are tapered to flat points 135, and the location of these levers is such that when they are swung upwardly from the full line position of Fig. 4, to the dotted line position this will bring the contact points against the lower run of the overlapped parts of band S directly beneath the platen so as to effect the welding operation.

In order that the overlapped sections of the band S will be held tightly together and also pressed tightly against the platen for the welding operation, I have provided each of the levers 130—130' with a presser pin 140 that extends upwardly therefrom at the outside of and somewhat beyond the contact. Each pin is slidably mounted in a bore 141 in its lever as seen in Fig. 7, and is pressed upwardly by a coiled spring 142 contained in the lower portion of the bore. A head 140' on the lower end of the pin limits its upward travel and serves as a base against which the spring may press. A plug 143 retains the spring in the bore. The presser pins are so arranged that, when the levers swing upwardly for the welding operation, their upper ends engage with the lower section of the band and lift it up tightly against the upper section and both are pressed tightly together and held firmly against the platen. Then when the contacts engage the band, a circuit will be closed to spot weld the overlapped sections together.

It will be stated here that the contact actuating levers 130 are well insulated in any suitable manner from the housing and each has a circuit connection 145 leading thereto. As shown in Figs. 6 and 7 the circuit connections are attached to the sides of the levers by bolts 146 and the connecting means is sufficiently flexible as not to interfere with their swinging action.

The means provided for actuating the contact mounting levers 130—130' is shown in Figs. 3 and 15. Mounted in the housing 71 are cam levers 148—148' pivotally supported by pivots 149. These levers are connected at their upper ends by links 150—150' with the levers 130—130' respectively. Mounted on each lever is a cam roller 151 and these are engaged, respectively, by cams 152—152' fixed on the shaft 78. Each cam is uniformly circular except at diametrically opposite sides each is provided with recesses 153—153' into which its rollers may drop when they come into registration. At their lower ends the levers have blocks 156 pivotally attached thereto through which guide bolts 157 are extended. These bolts have ends fixed in the housing 71 and at their other ends they mount coiled springs 158 which press against the blocks to urge the cam rollers against their respective cams.

75 The design of the cams 152—152' is such that

they normally retain the cam levers at positions whereby the welding contacts are held retracted; that is, swung downwardly and away from the platen, as shown in Fig. 4, at which positions they are clear of the path of travel of the band S as it is wrapped about a bundle. However, when the cams, during rotation, pass through these positions at which their cam rollers may drop into the cam recesses 153, the springs 158 will actuate the cam levers to swing the welding contacts upwardly and against the band S for the welding operation, but this period of contact for welding is only momentary as the cams stop rotation in the position shown in Fig. 11, thereby retaining the contacts in retracted position.

By proper setting of the cams 152—152' on the shaft 78, this welding operation will be caused to take place immediately following the overlapping of the band across the platen P. Also, by advancing one cam slightly with respect to the other, one contact may be caused to operate in advance of the other.

Immediately following the band welding operation, the ends of the band at opposite sides of the weld and at the inside of the grippers G and G² are severed to free the bundle for removal from the machine. This band cutting means consists of shearing points 165—165' mounted by the carriage 93 and extending forwardly therefrom closely adjacent the inside surfaces of the gripper jaws as seen in Fig. 2, and also as shown in the diagrammatic views of Figs. 18 and 23.

The carriage 93, which is slidably mounted in the main frame for movement toward and from the housing 71 is actuated in synchronism with action of the welding contacts by a cam 170 that is fixed on shaft 75. This cam is circular except that it is provided at diametrically opposite sides with humps 171—171' which are adapted to act 49 against a cam roller 172 mounted by a stud 173 on a lever arm 174 fixed on a cross shaft 175 supported in the housing 70 parallel with and below shaft 75. On shaft 175 there is also mounted a toothed segment 176 meshing with 45 rack teeth 177 on the under side of the carriage. A coiled spring 178 is attached to the arm 174 and to the housing 70 to pull the carriage outwardly thereby to retract the cutters to the position of Fig. 2. This outward travel of the carriage is limited by contact of the segment with a post 180 mounted adjustably in the rear wall of the housing as seen in Fig. 3. Forward travel of the carriage is effected by rotation of the shaft 75 and cam 170; it being apparent that as a hump 171 or 171' of the cam 170 engages with the cam roller 172 the lever 174 will be actuated forwardly and this will swing the geared segment 176 forwardly, thereby moving the carriage accordingly. As the carriage moves forwardly, the cutters 165—165' engage with the end of the band secured in gripper G and also with that portion secured in gripper G² to cut the band at the inside of the grippers and outside the weld, thus freeing the bundle from the band. To prevent rotation of the grippers during this cutting operation, the carriage is provided at its forward edge with slots 177 directly above the sliding jaws, and pins or studs 177a extend from the 70 jaws, as seen in Figs. 4 and 8. Thus, when the carriage moves forwardly for the band cutting operation, the studs are received in these slots and the jaws are thereby held against rotative action.

After the band has been secured about the bundle, it still underlaps the platen and must be pulled therefrom in order for removal of the bundle from the machine. For removal of the band from beneath the platen, I provide a stripper which is in the form of a downwardly yieldable hook 182 that is attached centrally to the carriage to extend forwardly therefrom. When the carriage moves forwardly for the shearing action, the hook yields beneath that portion of the band beneath the platen and then when the carriage moves outwardly immediately following the shearing of the band ends, the hook engages the band and strips it from beneath the platen, thus freeing the bundle for removal from the machine.

On return movement of the carriage, the gripper jaw which held the end of the band, retracts to an open position, but the other gripper which held that part of the band leading directly to the ring R retains its hold on the band in readiness for the next wrapping operation; this action being due to the setting of the cams 109—109' on shaft 75. The mode of operation of this machine provides that if an operation starts with the band held in gripper G, the next operation will start with the band held by gripper G² and vice versa.

By reference to Fig. 19 it will be observed that the end of the band S is held in gripper G, and it will be understood that when the cutters advance and clip the band after the welding operation, there will be a short piece of band left in the gripper jaw slot 97. Therefore, in order to remove such pieces left in either gripper jaw, and avoid any interference therefrom in the next gripping action, I have provided a knockout rod 190 within each gripper slide. These rods are slidably fitted inside of the tubular gripper slides and are fixed at their outer ends to the outer end walls of the housings 70 as seen in Fig. 4. The inner ends of the rods terminate within the slides when the latter are extended into gripping position, but when the slides are retracted, after an operation, as to the position of Fig. 4, they move inwardly along the rods and the severed pieces of band contained in the slot are ejected by contact with the rod end.

Assuming that the various parts are so constructed and are assembled as described, and that the motor is in operation and that a bundle has been placed in position as in Figs. 1 and 3a, the wrapping operation is as follows:

Starting with parts as shown in Figs. 1 and 18 with the binding band S drawn off from the supply, threaded through the tensioning means 7, wound about the slack take up sheaves 8 and 9, then extended over guide sheaves 10 and 12, then about the guide rollers 13 on ring R and passed between rollers 14—14' to gripper G; the end of the band being secured by hooking its end portion in the slot 97 of the gripper jaw 91.

It will here be stated that, if it is necessary, the gripper may be opened manually by applying a wrench or crank device to the end of shaft 75 and thereby rotating the shaft to a position at which the cam 109' will act on lever 122' to retract the gripper slide to open position for application of the end of band S to the slot 97. Then by further rotation, the gripper slide will be actuated forwardly to cause the cooperating parts 90—91 to grip and retain the end of the band as shown in Fig. 18.

To start the wrapping operation, either foot pedal 51 or 52 is depressed and this by setting clutch 26 and releasing the brake band 64 sets

the driving mechanism in operation to cause the ring gear R to rotate in a clockwise direction thereby carrying the band S around the bundle as will be observed by reference to the diagrammatic views of Figs. 19, 20 and 22, and bringing sections of the band in overlapped relation across the underside of the platen P, as in Fig. 13.

During the final rotative travel of the ring gear R, and while the run of the band from the ring gear is drawn directly across the path of travel 10 of the open gripper G² the shafts 75 and 73 are set in motion by action of cam wheels 85—86 on gears 81 and 82. Rotation of shaft 75, and cams 109 causes an action of lever whereby the pilot slides 120—120' are projected to lift the upper section of the band out of the path of travel of the forwardly moving gripper slide 91, which subsequently grips the lower section of the band and also out of line of travel of the cutters that later move forwardly to sever the band ends. 20 Thus, both ends of the band, as wrapped about the bundle, are securely held across the underside of the platen.

At the same time that shaft 75 starts its rotative operation for actuating the pilot slide 120 and 25 jaw of gripper G² to functional positions the shaft 78 starts rotation, and thus in proper sequence actuates the levers 130 carrying the welding contacts to bring the presser points and then the contacts momentarily against the overlapped 30 parts of the band, thus to weld them together; the contacts by reason of advance setting of one cam 152 relative to the other, successively engage the band so that overheating of the platen is avoided.

Immediately following the welding operation the carriage 93 is actuated forwardly as from the position shown in Fig. 22 to that of Fig. 23 and thereby causes the cutters to sever the band S at the inside of each gripper, thus freeing the 40 bundle from the grippers.

As the carriage comes forwardly for this band cutting operation, the stripper hook 182 yields beneath the welded sections of the band and then when the carriage retracts, the hook pulls 45 the band from beneath the anvil to free the bundle for removal from the machine. At the same time the jaw 91 of gripper G is drawn outwardly to open the gripper, but the jaw 91 of gripper G² remains extended so that that end of 50 the band is held for the next wrapping operation. Each wrapping operation is terminated by reason of a cam 60 on wheel 61 acting on trip dog 58 to release the clutch 26 and thus stop the same.

For the next wrapping operation, the ring gear 55 R rotates in a counterclockwise direction, starting from the position of Fig. 23, and finishes with the band being held also by gripper G.

While I have illustrated the present machine as being adapted to the welding of a flat metallic 60 band about the bundle, it is to be understood that it is just as well suited to welding of a wire since it would require only a slight alteration in the shape of the grooves of the guide rolls and sheaves which carry the wire and slight alteration or change in the grippers. The wire band W, when drawn across the platen in the same manner and by the same means provided by the band, would assume the superposed relationship shown in Fig. 24; it being understood that the 70 gripper jaws would be constructed so that when gripped onto the wire they will hold these overlapped strands in that position ready for the welding operation. Then, as soon as the welding was completed and the bundle released from the 75

machine, the tension in the wire band would cause the lapped portions of the joint to flatten against the underside of the bundle, as shown in Fig. 25.

5 Having thus described my invention, what I claim as new therein and desire to secure by Letters Patent is—

1. In a bundle wrapping machine having a reversible means for wrapping a band about a bundle for each direction of movement; a rotatable gripper and a mounting therefor adapted to receive the band therein unbent at the end of a wrapping operation in one direction and to rotate in its mounting to prevent bending this 15 end of the band when drawn by the wrapping means in the reverse direction.

2. In a bundle binding machine, means for wrapping a band in one direction about an object, a gripper operable to grip the band at the 20 end of the wrapping operation, a mounting for the gripper and means for causing the band subsequently to be wrapped in the reverse direction; said gripper being movable in its mounting thereby to avoid the secured end of the band being bent about the gripper incident to its reverse 25 wrapping.

3. In a bundle binding machine, means for wrapping a band in one direction about an object, a gripper comprising complementary parts 30 engageable with the band to grip it at the end of a wrapping operation, a mounting for the gripper and means for causing the band subsequently to be wrapped in the reverse direction; said gripper parts being revoluble in the mounting to permit movement that will prevent the end portion 35 of the band held therein being bent thereover incident to its reverse wrapping.

4. In a bundle binding machine, a bundle supporting means, a pair of grippers at one side of 40 support, means for actuating the grippers between open and closed positions, means for wrapping a metallic band, secured at its end in one gripper, about the bundle to cause opposite end portions to be overlapped between the grippers, means for closing the second gripper against 45 the overlapped portion of the band, means for joining the overlapping portions, means for severing the band between the joint and grippers, means for opening the first gripper and means 50 for causing a subsequent wrapping operation to be completed in a reverse direction; said grippers each being axially revoluble thereby to prevent the secured end of the band being bent about its gripper incident to a wrapping operation.

5. In a bundle binding machine including a 55 platen across which a bundle is located and means reversible for successive operations whereby, for each direction of wrapping, a band may be wrapped about the bundle and its ends disposed in overlapped relation across the platen; rotatable grippers and mountings therefor at opposite sides of the platen; said grippers being arranged alternately to receive and grip the end 60 of a band without bending it and adapted to rotate in their mountings to prevent bending of the gripped end of a band when the band is drawn by the wrapping means in the reverse direction.

6. In a bundle binding machine, means for supporting a bundle, a platen at one side of the bundle, means for passing a metallic band about the bundle and twice across the platen, means co-acting with the platen for welding together those 65 portions of the band crossing it, and a recipro-

cally movable means adapted to functionally engage the joined portions of the band to strip the bundle securing band from the platen.

7. In a bundle binding machine including a platen across which a bundle may be located, reversible means whereby a band may be wrapped, for each direction of travel, about the bundle and its ends disposed in overlapped relation across the platen; rotatable grippers and mountings therefor at opposite sides of the platen; said 10 grippers being arranged alternately to receive and grip the end of the band without bending it, at the end of successive wrapping operations, and being rotatable in their mountings under pull applied to the band by the wrapping to accommodate the band without bending it incident to a reversal in direction of the wrapping means, means for welding the overlapped ends of the band together, and a reciprocating slide with cutters thereon adapted to sever the ends of the 20 band at opposite sides of the weld.

8. In a bundle binding machine including a platen across which a bundle is located and reversible means whereby a band may be wrapped, for each direction of the said means, about a 25 bundle and its ends disposed in overlapped relation across the platen, rotatable grippers and mountings therefor at opposite sides of the platen to receive and grip the ends of the band and alternately serving for successive wrapping operations to anchor the initial end of the band, each gripper being adapted to receive the secondary end of the band therein without bending, and rotatably mounted to accommodate the band without bending it upon reversal of direction of 30 the wrapping means, means for welding the overlapped ends of the band together, a reciprocating slide with cutters thereon adapted to sever the ends of the band at opposite sides of the weld, and a hook mounted on the slide to pass beneath 40 the band during the cutting operation and to engage the band on retraction of the slide to strip the band from the platen.

9. In a device of the character described, a band gripper comprising complementary parts adjustable into spaced relation for the reception between them of a bundle wrapping band, one of said parts having a transverse slot opening to the end thereof within which the band will be received when the parts are moved together, and 50 the other part being adapted to engage the band to push it into the slot.

10. In a device of the character described, a band gripper comprising complementary parts adjustable into spaced relation for the reception between them of a bundle wrapping band, one of said parts having a transverse slot opening to the end thereof within which the band will be received when the parts are moved together and the other part having edge portions adapted to engage the band to push it into the slot and to bite 60 thereinto to prevent slippage of the band while in the slot.

11. In a device of the character described, a band gripper comprising relatively fixed and movable complementary parts adapted to be adjustably spaced to receive a flat band edgewise between them, one of said parts having a tapered notch at its end leading into a narrow transverse 70 slot into which the said band will be pushed by adjustment of the two parts together; the second part having sharpened opposite edge portions between which the end of the complementary part will be received and which will bite into the edge 75

of the band to hold it against longitudinal slip-page in the slot.

12. In a bundle binding machine, the combination with reversible means for wrapping a binding strip about a bundle, of a gripper comprising complementary parts in coaxial alignment, means for moving said parts into spaced relation to receive the end of the band between them at the end of a wrapping operation in one direction, and for closing them together to grip the band between them for wrapping in the reverse direction; said parts of the gripper being revoluble about their axes to accommodate the band without bending to the reverse direction of wrapping.

13. In a machine of the character described, the combination with means for passing a flat band about a bundle, of a gripper comprising an anvil portion having a V-shaped notch opening to the end thereof, and a jaw portion tapered at its end to fit within the notch, and formed also with a V-shaped notch transversely of the direction of the first notch and leading into a slot opening transversely through the jaw, means for moving the jaw away from the anvil to receive the bundle tying band between them, means for actuating the jaw toward the anvil to cause the band to be guided by the V-shaped notch into the said slot and to be held securely therein by pressure of the anvil thereagainst; said anvil and jaw being coaxially revoluble in their supports and automatically adjustable to accommodate the direction of extension of the band therefrom.

14. In a machine of the character described, a band gripper comprising a jaw having a transverse slot opening to the end thereof within which the end of a band may be secured by shifting the jaw from open to closed position, means for severing the band adjacent the gripper while held therein, means for adjusting the jaw to open position and means operable incident to this adjustment to eject the severed end portion of the band from the slot.

15. In a machine of the character described, a guideway, a gripper jaw longitudinally movable in the guideway having an end slot arranged to receive a bundle tying band therein by an endwise closing adjustment of the jaw toward the band and an ejector rod, fixed against movement, contained within the jaw and on which the jaw is slidably movable and whereby the band will be engaged and thereby ejected from the slot when the jaw is adjusted to an open position.

16. In a machine of the character described, in combination, bundle supporting means, a platen, means for passing a band about the bundle and overlapping its ends across the platen, means coacting with the platen for welding said overlapped portions of the band together, a reciprocally movable slide, band cutters on the slide adapted on its forward movement to sever the band between the grippers and weld, and a means movable with the slide engageable with the welded band as the slide moves in the opposite direction thereby to strip the band from the platen.

17. In a machine of the character described, in combination, means for supporting a bundle, a platen, a carrier for passing a band about the bundle to overlap portions thereof across the platen, means coacting with the platen for welding said overlapped portions together to secure the band about the bundle, a reciprocally movable slide, a pair of band cutters on the slide, a hook on the slide, a driving means for the carrier and means synchronized therewith and operable after the wrapping and welding operation to re-

ciprocate the slide thereby to cause the cutters to sever the ends of the band at opposite sides of the weld and the hook to engage and strip the band from the platen after it has been severed.

18. In a machine of the class described, in combination, a bundle supporting means, a platen, a band gripper at opposite sides of the platen, means for passing a band, held in one gripper, about the bundle and twice across the platen, means for causing the band then to be gripped by the second gripper, means operable incident to the completion of the wrapping operation to coact with the platen to weld the overlapped parts together, a reciprocally movable slide, a cutter on the slide adapted, when the slide moves inwardly, to cut the band between the second gripper and the weld, means movable in advance of the cutter to lift the bundle securing portions of the band clear of the path of the cutter and means movable with the slide operable as the slide moves outwardly to strip the band from the platen.

19. In a machine of the character described, in combination, means for passing a band about a bundle and to dispose its opposite ends in overlapped relation, grippers for holding the ends of the band, means for welding the overlapped portions of the band together, a reciprocally movable slide, cutters on the slide for severing the ends of the band between the grippers and the weld, a rack associated with the slide, a gear meshing with the rack, a cam shaft, and a cam on the shaft operable to actuate the gear to effect reciprocation of the slide.

20. In a machine of the character described, in combination, means for passing a band about a bundle to bring opposite ends thereon into overlapped relation, grippers for engaging the ends of the band, means for welding the overlapped portions of band together, a reciprocally movable slide, cutters on the slide for severing the band ends at opposite sides of the weld, a revolvable cam shaft, cams on the shaft, and means actuated by the cams for actuating the slide and for actuating the grippers between open and closed positions.

21. In a machine of the character described, in combination, with means for wrapping a binding band about a bundle to bring opposite ends thereof into overlapped relation, means for welding the overlapped ends together, grippers for holding the ends of the band prior to welding, a reciprocally mounted slide, a rack on the slide, reciprocally movable means for opening and closing the grippers, a rotatably driven cam shaft, a cam on the shaft for alternately actuating the grippers between open and closed positions, a gear segment meshing with the rack, and a cam on the cam shaft for actuating the gear segment to reciprocate the slide and cutters on the slide for severing the ends of the band at opposite sides of the weld.

22. A device, as in claim 21, wherein means is movable in advance of the cutters to lift the bundle securing portion of the band clear of the path of said cutters.

23. In a bundle binding machine having a bundle support, a welding anvil and a rotatable carrier for passing a metallic band about a bundle on said support and twice across the welding anvil to bring opposite end portions of the band into overlapped relation across the anvil, means at one side of the anvil for holding the primary end of the band, an open gripper at the opposite side of the anvil within which the band is dis-

posed by the carrier both times it is passed across the anvil, a slide movable in timed relation with the carrier to offset the primary end portion of the band from the open gripper, and 5 means operable at the end of a wrapping operation for closing the gripper on the secondary end of the band.

24. In a bundle binding machine having a bundle support, a welding means and a carrier member for passing a metallic band about a bundle on the support and to dispose its primary and secondary end portions in overlapped relation twice across the welding means; means at 10 one side of the welding means for holding the primary end of the band, an open gripper at the opposite side of the welding means within which the band is disposed both times it is passed across the welding means, a slide movable in timed relation with the carrier against the primary end 15 portion of the band to offset it toward the bundle from the gripper; and serving, while so holding the primary end, as a positioning means against which the secondary end portion will be disposed by the carrier to align it accurately with the gripper, and means for closing the gripper against the secondary end portion of the band. 20

25. In a bundle binding machine having a bundle support, a welding means, band grippers at opposite sides of the welding means, a carrier member revoluble about an object on the support, and reversible for successive operations, for lay- 30

ing a metallic band, for each direction of rotation, about a bundle on the support, to bring the primary and secondary end portions thereof into overlapped relation adjacent the welding means, a gripper for holding the primary end of the band during the wrapping operation, a gripper for receiving the secondary end of the band, a slide associated with each gripper, means operable in timed relation with the carrier member for causing the slide that is associated with the gripper that is to receive the secondary end portion of the band to displace the primary end portion from alignment with the gripper, means for closing the gripper against the secondary end of the band, means for causing the welding means to weld the overlapped ends of the band together, means operable following each welding operation for severing the ends of the band between the weld and the grippers, and means for opening the gripper which held the primary end of the band. 25

26. In a machine of the character recited in claim 25 wherein the welding means includes an anvil across which the primary and secondary ends of the band are overlapped for welding and wherein the means for severing the ends of the band following the welding, is reciprocally movable and effects the severing while moving in one direction, and has a hook thereon for engaging the band when moving in the opposite direction to strip the band from the anvil. 30

CHARLES E. EVANS.
